(57) **CLAIM**

The ornamental design for a UV light connector set, as shown and described.

DESCRIPTION

FIG. 1 is a front, top, left side isometric view of a male UV light connector of a UV light connector set, shown separately to show aspects of the design not visible when in a connected configuration;

FIG. 2 is a front, top, right side isometric view thereof;

FIG. 3 is a front, bottom, left side isometric view thereof;

FIG. 4 is a front, bottom, right side isometric view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof;

FIG. 10 is a right side elevation view thereof;

FIG. 11 is a front, top, left side isometric view of a female UV light connector of the UV light connector set, shown separately to show aspects of the design not visible when in a connected configuration;

FIG. 12 is a front, top, right side isometric view thereof;

FIG. 13 is a front, bottom, left side isometric view thereof;

FIG. 14 is a front, bottom, right side isometric view thereof;

FIG. 15 is a front elevation view thereof;

FIG. 16 is a rear elevation view thereof;

FIG. 17 is a top plan view thereof;

FIG. 18 is a bottom plan view thereof;

FIG. 19 is a left side elevation view thereof;

FIG. 20 is a right side elevation view thereof; and,

FIG. 21 is a top isometric view of the male UV light connector and female UV light connector of the UV light connector set, shown in a connected configuration.

The broken lines depict portions of the article and environmental subject matter that form no part of the claimed design.

1 Claim, 19 Drawing Sheets
